His Attorneys.

UNITED STATES PATENT OFFICE.

JAMES J. HENNESSY, OF NEW YORK, N. Y.

PUMP FOR LUBRICATORS OR THE LIKE.

Application filed October 17, 1923. Serial No. 668,996.

My invention relates to pumps especially adapted for lubricators such as are to be used in journal boxes and driving boxes of railway rolling stock such as are illustrated in my previous Patents, Nos. 1,412,740, 1,412,741, and 1,416,710.

In lubricators of this type lubricant is supplied to the journal to which they are applied from a reservoir by means of a pump which is operated by relative movement of the journal or hub in the journal box. The movement of these parts, which is always present in railroad construction, varies in extent and consequently in the amount of lubricant supplied to the journal. I have found it highly desirable to limit the amount of lubricant supplied to the journal and while the above mentioned patents of mine have disclosed means for adjusting the pump stroke or discharge, these adjustments must be made by one who installs or inspects the lubricators and often under conditions which render accurate adjustment difficult or haphazard. In my improved construction herein disclosed the lubricator may be installed in any box and will supply a constant amount of lubricant to the journal irrespective of the exact form of the journal or movement of the journal in the box.

In the accompanying drawings which illustrate a selected embodiment of my invention—

Figure 1 is a vertical longitudinal section through a lubricator containing my improved pump and showing the complete device applied to the journal of a wheeled axle.

Figures 2 and 3 are detail sections corresponding to the section shown in Figure 1 but showing the parts in different operating positions.

The body 1 of the lubricator forms a lubricant reservoir 2 and is provided with ends and sides 3 which extend upwardly to points adjacent the surface of the journal A to which the device is applied. These walls have shoulders 4 which seat a waste pan 5 which is movable vertically of the body and is yieldingly held against the journal by means of a coiled spring 6 compressed between the same and a suitable seat 7 upon the body. This construction does not depart from earlier disclosures of mine.

The lower portion of body 1 includes an integral cylinder forming boss 8, one end of which is provided with an intake valve 9 con-

necting the cylinder interior with the lubricant reservoir 2. Slidable in cylinder 8 is a bushing 10 and slidable in bushing 10 is a piston 11, one end of which projects from the end of cylinder 8 opposite intake valve 9 and is there connected by means of a bar 12 with a contact rod 13 slidable in the end wall of the body and projecting outwardly through the latter into contact with the hub B or other vertical surface provided on journal A. Obviously movement to the right of the surface B longitudinally of the journal axis will move rod 13 inwardly, compressing a spring 14 seated in a suitable recess in the lubricator body and thereby moving piston 11 to the right. Upon shifting of surface B to the left spring 14 will press rod 13 outwardly and this reciprocation of the rod and piston will produce a pumping action in cylinder 8. It will be noticed that the cylinder is provided with a discharge passage 15 equipped with a check valve 16 and leading to a telescoping tube 17 extending through the waste in pan 5 to the surface of the journal A.

Obviously if piston 11 was solid the amount of lubricant received through valve 9 and discharged through valve 16 would depend upon the movement of the piston which would vary due to the relative play permitted between journal A and the lubricating device. To eliminate this variation in the operation of the pump I provide the bushing 10 in cylinder 8 and surrounding the forward portion of piston 11. Bushing 10 is provided with annular shoulders 19 at its ends and piston 11 is shaped so as to be engaged by these shoulders. The distance between shoulders 19 is about one-fourth inch greater than the length of the portion of piston 11 which engages the shoulder.

Piston 11 is hollow through a portion 20 of its forward end and is provided with one or more lateral ports 21. Bushing 10 is provided with an annular groove 22 and with one or more lateral ports 23 leading from this groove and adapted to be aligned with piston port 21 when the piston engages the righthand shoulder 19 of the bushing. The adjacent portion of the inner wall of cylinder 8 is recessed as indicated at 24. This recess is of such area that bushing port 23 is always open to the same. One or more ports 25 connect cylinder recess 24 with the exterior of the cylinder.

Assuming the parts to be in the position shown in Figure 1, it will be seen that port 21 and groove 22 are disaligned and movement of the piston to the right will close in-
 5 take valve 9 and will compress the fluid in cylinder 8, lifting check valve 16 and forcing fluid through passage 15 until the inner end of the piston approaches righthand shoulder 19 of bushing 10, as indicated in
 10 Figure 2. At this point the piston and bushing ports will be aligned and the fluid in cylinder 8 may by pass into the reservoir through these ports and the recess 24 and ports 25 in cylinder 8. At the beginning of
 15 the return movement of the piston port 21 will leave groove 22 as shown in Figure 3 thereby sealing the interior of the cylinder from its exterior and causing further movement to open intake valve 9 and recharge the
 20 cylinder and hollow piston with lubricant. The amount of fluid supplied by the pump is limited by the area of the cylinder and piston interior and by the excess of the distance between shoulders 19 and the corresponding
 25 portion of the piston. These elements may be controlled by the manufacture of the devices and permit the lubricator to be applied to any suitable journal without regard to adjustment of the operating mechanism or
 30 the giving of other consideration to the control of the supply of lubricant.

Various modifications of the details of my invention may be made without departing from the spirit thereof as expressed in the
 35 appended claims.

I claim:

1. In a pump, a cylinder, intake and discharge valves in said cylinder, a bushing slideable in said cylinder, and a piston having
 40 a limited sliding movement in said bushing, said cylinder, bushing, and piston having ports arranged so as to be disaligned during a predetermined movement only of said piston to render the latter operative and to be aligned during any remaining movement of said piston to provide a by-pass for the escape of fluid in said cylinder.

2. In a pump, a cylinder having a valved intake, a discharge passage leading from
 50 said cylinder, a reciprocating piston in said cylinder, a piston operating element adapted to be moved varying distances by an operating agency, a by-pass through said piston from the interior of said cylinder to the exterior thereof, and means for closing said by-pass during a limited movement of said piston only.

3. In a pump, a cylinder, intake and discharge valves in said cylinder, a bushing
 60 slideable in said cylinder, a piston having a limited sliding movement in said bushing, said cylinder, bushing and piston having ports arranged so as to be disaligned during a predetermined movement only of said piston to render the latter operative and to

be aligned during any remaining movement of said piston to provide a by-pass for the escape of fluid in said cylinder, and means for reciprocating said piston varying distances.

4. In a pump, a cylinder, intake and discharge valves in said cylinder, a bushing slideable in said cylinder, a piston having a limited sliding movement in said bushing, said cylinder, bushing and piston having ports arranged so as to be disaligned during a predetermined movement only of said piston in its discharge stroke and during substantially all of its intake stroke and to be aligned during the remainder of the piston discharge stroke to provide a by-pass for fluid trapped in the cylinder thereby limiting the discharge of fluid by said pump during each stroke irrespective of the length of said stroke.

5. In a pump, a cylinder, intake and discharge valves in said cylinder, a bushing slideable in said cylinder, a hollow piston slideable in said bushing, stops on said bushing limiting the movement of said piston therein, a lateral port in said piston, a lateral port in said bushing adapted to align with said piston port only when said piston engages one of said stops, a port in said cylinder always in communication with said bushing port, and piston operating means having variable movement.

6. In a pump, a cylinder, a discharge passage, an inlet passage, a piston in said cylinder for forcing fluid through said passage, means having varying movement for operating said piston, and means in said cylinder and surrounding said piston for limiting the discharge of said piston to said passage.

7. In a pump, a cylinder provided with a port in its side, intake and discharge valves for said cylinder, a hollow piston in said cylinder provided with a port in its side, a movable member between said ports and having a port adapted to be aligned with said piston and cylinder ports or to be moved out of alignment therewith, and cooperating elements on said piston and member whereby movement of said member is effected by said piston.

8. In a pump, a cylinder provided with a port in its side, intake and discharge valves for said cylinder, a hollow piston in said cylinder provided with a port in its side, a movable member between said ports and having a port adapted to be aligned with said piston and cylinder ports or to be moved out of alignment therewith, and means for moving said member when said piston is moved beyond a predetermined extent.

9. In a pump, a cylinder, an inlet thereto, a discharge outlet therefrom, a piston in said cylinder adapted to be reciprocated between terminal points which may vary longitudinally of the cylinder with successive strokes

- of said piston, and means operable by said piston for limiting the discharge of said piston through said outlet irrespective of the location of said terminal points relative to said discharge outlet.
10. In a pump, a cylinder, an inlet thereto, a discharge outlet therefrom, a piston in said cylinder adapted to be reciprocated between terminal points which may vary longitudinally of the cylinder with successive strokes of said piston, and means operable by said piston for limiting the discharge of said piston through said outlet irrespective of the location of said terminal points relative to
- said discharge outlet and irrespective of the 15 distance between said terminal points.
11. In combination, a pump cylinder, an inlet thereto, a discharge outlet therefrom, a piston, a reciprocating member, and means operable by said member for limiting the 20 discharge by said piston through said outlet irrespective of variations in the location of terminal points of the movement of said member on successive strokes thereof.
- In testimony whereof I hereunto affix my 25 signature this 14th day of September, 1923.

JAMES J. HENNESSY.
